UNITED STATES PATENT OFFICE.

WILLARD T. SEARS, OF MONTCLAIR, NEW JERSEY, ASSIGNOR TO NILES-BEMENT-POND COMPANY, OF NEW YORK, N. Y., A CORPORATION OF NEW JERSEY.

SUPPORTING AND CLAMPING MECHANISM FOR DRILLING-MACHINES.

1,376,169.

Specification of Letters Patent. Patented Apr. 26, 1921.

Application filed April 22, 1918, Serial No. 229,999. Renewed November 9, 1920. Serial No. 422,960.

To all whom it may concern:

Be it known that I, WILLARD T. SEARS, a citizen of the United States, residing at Montclair, in the county of Essex and State 5 of New Jersey, have invented certain new and useful Improvements in Supporting and Clamping Mechanisms for Drilling-Machines, of which the following is a specification.

One of the objects of the invention is to provide an improved mechanism of the general type set forth in my patent for radial drills, No. 1,089,442 dated March 10th, 1914. In accordance with the present invention, I 15 provide improved devices, preferably located at the center of the drill column, whereby the column is supported so as to be freely rotatable and whereby it may be clamped so that it is firmly held against rotation and rigidly supported to resist the reaction of drilling. Other objects will be apparent from the following specification and claims.

In the accompanying drawings I have 25 shown the embodiment of the invention which is now deemed preferable, but it will be understood that modifications and substitutions of equivalents can be made within the scope of the appended claims without departing from the spirit of the invention.

Of the drawings:

Figure 1 is an elevational view of a drilling machine embodying the invention.

Fig. 2 is a longitudinal vertical sectional view through the base, the column being turned at right angles to the position shown in Fig. 1.

Fig. 3 is a horizontal sectional view taken along the line 3—3 of Fig. 2.

Fig. 4 is a fragmentary sectional view taken along the line 4—4 of Fig. 2.

Fig. 5 is a fragmentary horizontal sectional view taken along the lines 5—5 of Figs. 2 and 4.

Referring to the drawings, 1 and 2 represent the base of the drilling machine. Mounted upon the base for movement about a vertical axis is a column 3. Preferably, as indicated in Fig. 2, this column is divided or formed in two parts 3^a, 3^b, as shown in my Patent 1,071,590 dated August 26th, 1918. Supported on the column and preferably vertically movable with respect thereto is a horizontal arm 4 along which is slidable 5 a saddle 5 carrying a head provided with a

rotatable spindle 6. Preferably the arm 4 or a carrying member therefor extends through the column between the two parts 3^a, 3^b thereof and directly supports a gear casing 7 and an electric motor 8. From the motor 8 power is transmitted through gearing in the casing 7 to the main power shaft 9 extending longitudinally of the arm and thence to the spindle 6. The mechanisms thus far described do not of themselves constitute any part of the present invention and they can be considerably modified as required.

The column 3 preferably is provided with an extension 10 which projects downward 70 into the base parts 2 and 1. This extension is engaged by two bearings which serve to hold the column in axially fixed position and which at the same time permit turning movement. At 11 there is a roller bearing 75 interposed between the extension 10 and the upper part of the base section 2. At 12 there is a bearing interposed between the lower end of the extension 10 and a cupped plate 13 secured to the lower base section 1. 80

For carrying the weight of the column and of the associated parts during turning movement, there is provided a bearing preferably in the form of an anti-friction support, and preferably located at the axis of 85 the column. As illustrated this support is in the form of a ball thrust bearing 14. The lower race of this bearing rests upon the before mentioned plate 13 and the upper race of the bearing engages a flange at the 90 lower end of a vertical shaft 15. This shaft fits central apertures in the extension 10 and is relatively slidable therein, being connected with the extension and with the column by special mechanism to be now described.

Interposed between the top of the shaft 15 and the column is a spring mechanism which serves to carry the column and associated parts when they are rotated. As illustrated, a carrier member 16 is fitted to the upper end of the shaft 15. Projecting from the member 16 at opposite sides thereof are brackets 17, 17, the top surfaces of these brackets being transversely curved, as indicated. Preferably, as shown in Fig. 5, the brackets extend into notches 18, 18 in the extension 10, the member 16 being thus prevented from turning relatively to the extension. Resting on the brackets 17, 17 are 110

springs 19, 19 each preferably consisting of several parallel leaves. The springs 19, 19 extend into slots or notches 20, 20 in the extension 10 of the column 3.

5 Means is provided for effecting relative adjustment to regulate the spring pressure. As illustrated, the carrier member 16 is provided with a central threaded aperture in which fits a screw 21, the bottom of this 10 screw engaging the top of the shaft 15. The bottom of the column 3 is provided with a horizontal surface 22 adapted under certain conditions to engage a horizontal surface 23 on the top of the base section 2. In assembling, the surfaces 22 and 23 will be initially 15 in contact. The screw 21 is then turned so as to raise the carrier member 16 with respect to the shaft 15. This turning movement is continued until the carrier member 20 16, acting through the springs 19, serves to lift the column 3 and the parts carried thereby entirely clear of the base 2. Then the screw 21 is clamped in adjusted position by means of a lock nut 24. In this way the 25 surfaces 22 and 23 are separated and the entire weight of the column and associated parts is supported on the shaft 15 and thus on the ball thrust bearing 14. In the drawings, the distance between the surfaces 22 and 23 is considerably exaggerated, and it is 30 to be understood that in practice this distance may be only a few thousandths of an inch.

The positions and relative weights of the 35 motor and of the arm together with the saddle and drill head are such that under ordinary conditions the resultant center of gravity is approximately at the center of the column and therefore vertically above 40 the ball bearing 14. With the surfaces 22 and 23 out of engagement and with the weight of the parts substantially balanced on the bearing 14, it is possible to swing the column and the arm very easily.

45 After the arm has been swung to the desired position the column is clamped by the mechanism to be now described. In the embodiment of the invention as shown, the clamping mechanism applies pressure to the 50 column downward in opposition to the spring mechanism, thus forcing the surface 22 into engagement with the surface 23.

Carried by the extension 10 near the bottom thereof, is a ring 25 having a downward and 55 outward inclined upper surface. Preferably the ring is provided with spaced notches 26, 26 and the extension 10 is provided with similarly spaced lugs 27, 27. In assembling, the notches 26 of the ring are brought into 60 alinement with the lugs 27, 27 of the projection, thus permitting the ring to be moved upward to the level shown. Then the ring is turned so that the parts thereof between the notches will rest upon the lugs. For 65 holding the ring in this position there is

provided a key 28 engaging a keyway in the extension 10.

The base section 2 is provided with an inward extending flange 29 having a horizontal bottom surface positioned immediately above the top surface of the ring 25. Interposed between the ring 25 and the flange 29 is a split ring 30 having bottom and top surfaces adapted respectively to engage the top surface of the ring 25 and the 70 bottom surface of the flange 29. Preferably, as shown, the top surface of the ring 25 is cut away at opposite quadrants so that there will be contact between the ring 25 and the ring 30 only at the remaining quadrants 32 80 and 33. A lug 34 on the base section 2 projects into a notch in the ring 30 to prevent the ring from turning. The ring 30 carries two apertured ears 35 and 36 through which extends a threaded rod 37. A pin 38 projecting through a slot in one of the ears prevents the rod 37 from turning. At one end the rod 37 is engaged by lock nuts and washers 39 and at the other end it is engaged by a threaded sleeve 40, this sleeve being provided with a lever or handle 41.

When the surfaces 22 and 23 are separated, as shown in Fig. 2, the lever 41 is in a vertical position, as indicated in Fig. 3. When the lever is moved in the counter-clockwise direction to the position shown in Fig. 1, the two ears 35 and 36 are drawn together, thus contracting the ring 30 and forcing it into the wedge-shaped space between the ring 25 and the flange 29. This 95 wedging action forces the ring 25 downward, the ring carrying with it the extension 10 and the column 3 together with all the parts associated therewith. This downward movement flexes the springs 19, 19 10 and brings the surface 22 into firm contact with the surface 23. In this way the arm and the column are clamped against angular movement, the clamping being effected not only by the engagement of the ring 30 with the ring 25 and with the flange 29, but also by the engagement of the surface 22 with the surface 23. When the parts are thus clamped the column 3 is very firmly supported so as to resist the reaction on the 11 spindle during the drilling operation.

What I claim is:

1. In a drilling machine having a base, a column rotatably supported on the base and drilling mechanism carried by the column, the combination of a column-support at the axis of the column, and vertically acting clamping means adapted to effect a direct engagement between the column and the base supplemental to the said support, the 12 column being chiefly carried directly by the base when the said clamping means is engaged and being carried entirely on the support when the said clamping means is disengaged.

2. In a drilling machine having a base, a column rotatably supported on the base and drilling mechanism carried by the column, the combination of a column-support, vertically acting clamping means adapted to effect a direct downward engagement of the column with the base, and spring mechanism acting directly on the column vertically upward in opposition to the clamping means, the column being chiefly carried directly by the base when the said clamping means is engaged and being carried entirely on the support by means of the spring when the said clamping means is disengaged. 70

7. In a drilling machine having a base, a column rotatably supported on the base and drilling mechanism carried by the column, the combination of an anti-friction column-support, means for applying a downward pressure to the column to effect a direct clamping engagement between the column and the base, spring mechanism interposed between the support and the column and acting directly on the column upward in opposition to the clamping means, and means for effecting relative adjustment to regulate the spring action so that the column is carried entirely on the support when the clamping means is released. 80

8. In a drilling machine having a base, a column rotatably supported on the base and drilling mechanism carried by the column, the combination of an anti-friction column support, means for applying a downward pressure to the column to effect a direct clamping engagement between the column and the base, spring mechanism interposed between the support and the column and acting directly on the column upward in opposition to the clamping means, and adjusting means between the support and the spring mechanism to regulate the spring action so that the column is carried entirely on the support when the clamping means is released. 90

9. In a drilling machine having a base, a column rotatably supported on the base and drilling mechanism carried by the column, the combination of a vertical shaft at the center of the column, an anti-friction bearing at the bottom of the shaft, means for applying a downward pressure to the column to effect a clamping engagement between the column and the base, and spring mechanism interposed between the top of the shaft and the column and acting upward in opposition to the clamping means, the column being carried entirely on the shaft by means of the spring mechanism when the clamping means is released. 105

10. In a drilling machine having a base, a column rotatably supported on the base and drilling mechanism carried by the column, the combination of a vertical shaft at the center of the column, an anti-friction bearing at the bottom of the shaft, means for applying a downward pressure to the column to effect a clamping engagement between the column and the base, spring mechanism interposed between the top of the shaft and the column and acting upward in opposition to the clamping means, and 115

120

125

130

2. In a drilling machine having a base, a column rotatably supported on the base and drilling mechanism carried by the column, the combination of a column-support, vertically acting clamping means adapted to effect a direct downward engagement of the column with the base, and spring mechanism acting directly on the column vertically upward in opposition to the clamping means, the column being chiefly carried directly by the base when the said clamping means is engaged and being carried entirely on the support by means of the spring when the said clamping means is disengaged. 10

3. In a drilling machine having a base, a column rotatably supported on the base and drilling mechanism carried by the column, the combination of a column-support, means for applying a downward pressure to the column to effect a direct clamping engagement between the column and the base, spring mechanism interposed between the support and the column and acting directly on the column upward in opposition to the clamping means, and means for effecting relative adjustment to regulate the spring action so that the column is carried entirely on the support when the clamping means is released. 20

4. In a drilling machine having a base, a column rotatably supported on the base and drilling mechanism carried by the column, the combination of an anti-friction column-support at the axis of the column, and vertically acting clamping means adapted to effect a direct engagement between the column and the base supplemental to the said support, the column being chiefly carried directly by the base when the said clamping means is engaged and being carried entirely on the support when the said clamping means is disengaged. 30

5. In a drilling machine having a base, a column rotatably supported on the base and drilling mechanism carried by the column, the combination of an anti-friction column-support, vertically acting clamping means adapted to effect a direct downward engagement of the column with the base, and spring mechanism acting directly on the column vertically upward in opposition to the clamping means, the column being chiefly carried directly by the base when the said clamping means is engaged and being carried entirely on the support by means of the spring when the said clamping means is disengaged. 40

6. In a drilling machine having a base, a column rotatably supported on the base and drilling mechanism carried by the column, the combination of an anti-friction column-support at the axis of the column, vertically acting clamping means adapted to effect a direct downward engagement of the column with the base, and spring mecha-

means for moving the spring mechanism upward or downward with respect to the shaft so that the column is carried entirely on the shaft by means of the spring mechanism 5 when the clamping means is released.

11. In a drilling machine having a base, a column rotatably supported on the base and drilling mechanism carried by the column, the combination of a vertical shaft at 10 the center of the column, an anti-friction bearing at the bottom of the shaft, means for applying a downward pressure to the column to effect a clamping engagement between the column and the base, a carrier member at 15 the top of the shaft, and horizontal springs engaging the carrier member at their centers and the column at their ends, the springs acting upward in opposition to the clamping means and serving to entirely support 20 the column when the clamping means is released.

12. In a drilling machine having base, a column rotatably supported on the base and drilling mechanism carried by the column, the combination of a vertical shaft at 25 the center of the column, an anti-friction bearing at the bottom of the shaft, means for applying a downward pressure to the col-

umn to effect a clamping engagement between the column and the base, a carrier member at the top of the shaft, horizontal springs engaging the carrier member at 30 their centers and the column at their ends, the springs acting upward in opposition to the clamping means and serving to entirely support 35 the column when the clamping means is released, and a screw threaded into the carrier member and engaging the top of the shaft for adjusting the carrier member upward or downward. 40

13. In a drilling machine the combination of a base, a column rotatably supported on the base, drilling mechanism carried by the column, spaced integral lugs formed on the column, a ring surrounding the column and 45 having similarly spaced notches in its inner edge whereby the ring may be moved past the lugs and then turned to be supported thereby, a flange on the base adjacent the ring, a split ring engaging the first said 50 ring and the flange, and means for contracting the split ring to effect clamping.

In testimony whereof, I hereto affix my signature.

WILLARD T. SEARS.
